UNITED STATES PATENT OFFICE.

HARRY F. LÖWENSTEIN, OF WASHINGTON, DISTRICT OF COLUMBIA, ASSIGNOR OF ONE-HALF TO HUGH S. HILL, OF WASHINGTON, DISTRICT OF COLUMBIA.

ILLUMINATED SIGN.

1,168,084.

Specification of Letters Patent. Patented Jan. 11, 1916.

Application filed October 17, 1914. Serial No. 867,101.

To all whom it may concern:

Be it known that I, HARRY F. LÖWENSTEIN, a citizen of the United States, residing at Washington, in the District of Columbia, have invented certain new and useful Improvements in Illuminated Signs, of which the following is a specification.

The present invention relates to certain new and useful improvements in illuminated signs, and has for its object to provide a device of this character which embodies novel features of construction whereby any selected one of a pair of designs upon a cover plate for a lamp box may be illuminated or displayed to the exclusion of the other design, even though said designs may have overlapping portions.

A further object of the invention is to provide an illuminated sign of this character which is very simple and compact in its construction and is well adapted for use for general advertising purposes, as a rear end signal upon vehicles, as a traffic signal at street intersections, or for other signaling purposes.

A still further object of the invention is to provide an illuminated signal device which is simple and inexpensive in its construction, which can be easily operated from a distance, and which admits of the designs being superposed upon each other so as to economize in space and eliminate the necessity of providing an independent space or area for each design which it may be desired to use.

With these and other objects in view, the invention consists in certain novel combinations and arrangements of the parts as will more fully appear as the description proceeds, the novel features thereof being pointed out in the appended claims.

For a full understanding of the invention, reference is to be had to the following description and accompanying drawing, in which:

Figure 1 is a plan view of the front of a lamp box constructed in accordance with the invention and showing a possible arrangement of transparent jewels for displaying either of the words "Right" or "Left" together with an arrow which may be caused to point in either direction. Fig. 2 is a similar view of the front of a lamp box, showing a possible arrangement of transparencies for displaying either of the words "Pass" or

"Stop", and Fig. 3 is an elevation of the lamp box with the cover removed, showing the arrangement of lamps therein together with the switch for operating the same.

Corresponding and like parts are referred to in the following description and indicated in all the views of the drawing by the same reference characters.

The operation of the device is based upon the fact that where lights of complementary colors are used the rays from either one of the lights will pass through a correspondingly colored transparency or an uncolored transparency, but will be for all practical purposes completely absorbed in passing through a transparency of the opposite complementary color. Overlapping designs may thus be placed upon the same plate, those portions of the plate common to both designs being provided with uncolored transparencies through which either color of light will pass, while the remaining portions of the two designs are formed with respective transparencies colored to correspond with the colors of the complementary lights.

Referring to Fig. 1, the numeral 1 designates the cover of a lamp box, said cover being formed of any suitable opaque material and being provided with a series of openings adapted to receive the usual jewels or lenses 2 and arranged so that either of the words "Right" or "Left" may be displayed in connection with an arrow pointing in either direction. The two words "Right" and "Left" are superposed directly upon each other and those portions of the letters of the two words which are common to each other are formed by uncolored jewels or lenses 2^a. In a similar manner the body portion of the double headed arrow which is arranged under the words "Right" and "Left" is formed of the uncolored jewels 2^a. The complementary colors red and green may be used, and those portions of the design which are peculiar to the letters of the word "Right" are formed by the green colored jewels 2^b, while those portions of the design which are peculiar to the letters of the word "Left" are formed by the red colored jewels 2^c. In a similar manner, the green colored jewels 2^b are used to form the head at the right hand end of the arrow, while the red colored jewels 2^c are used to form the head at the left hand end of the arrow.

The opaque plate 1 with the transparen-

des arranged therein as previously described is designed to be employed as the cover for a lamp box 4 such as is shown by Fig. 3. Arranged within this lamp box is a pair of electric lights 5 and 6, the lamp 5 being adapted to give a red light while the lamp 6 is adapted to give a green light. Either the red light or the green light will pass through the uncolored transparencies or jewels 2^a. The red light from the lamp 5 will pass through the uncolored transparencies 2^a and the red transparencies 2^b, but will be absorbed in passing through the green transparencies 2^c. The portions of the overlapping designs formed by the green transparencies 2^c will thus be suppressed when the red light is used, although that particular design which is formed by a combination of the uncolored transparencies and red transparencies will be illuminated in red.

With the arrangement shown by Fig. 1, it will be seen that when the red light is used the word "Left" will be illuminated in red and the arrow illuminated in red so as to point to the left. In a similar manner when the green light 6 is used, the rays of green light will pass through the uncolored transparencies 2^a and the green transparencies 2^c but will be absorbed in passing through the red transparencies 2^b. This will result in displaying the word "Right" in green together with a green arrow pointing to the right.

Fig. 2 shows another possible combination of transparencies by means of which either of the words "Pass" or "Stop" may be illuminated while the other word is suppressed. The numeral 3 is an opaque plate similar to the plate 1 and having suitable transparencies therein. The transparencies 3^a are uncolored and are common to both of the words "Pass" and "Stop." The transparencies 3^b are colored green and are peculiar to the word "Pass," while the transparencies 3^c are red and peculiar to the word "Stop." It will thus be obvious that when the red light 5 is used the word "Stop" will be illuminated in red, since the red light will pass through the uncolored transparencies 3^a and the red transparencies 3^c, but will be absorbed in passing through the green transparencies 3^b. In a similar manner when the green light 6 is used the word "Pass" will be illuminated in green, since the green light will pass through the uncolored transparencies 3^a and the green transparencies 3^b, but will be absorbed in passing through the red transparencies 3^c. In a similar manner any two words or designs may be superposed upon each other and those portions which are common to the two words or designs formed by uncolored transparencies while those portions which are peculiar to the respective designs are formed by transparen-

cies of complemental colors. With this arrangement a light of one of the complemental colors will cause one of the designs to be illuminated to the exclusion of the first design. By thus superposing the designs upon each other a very compact arrangement is produced and the necessity of having several separate words or designs upon the same plate is eliminated. This is an advantage in many cases, since otherwise it would be necessary to use an objectionably large plate or to make the several words or designs so small as not to be readily distinguished at a distance.

Any suitable means may be provided for controlling the electric lights 5 and 6, and in the present instance a wire 7 is shown as leading from one of the terminals of each of the lamps to a suitable source of electric supply such as the batteries 14. The other terminals of the two lamps 5 and 6 are connected by the respective wires 9 and 8 to the contacts 11 and 10 of a suitable switch. The switch lever 12 is connected by a wire 13 to the batteries 14 and is adapted to be swung into engagement with either of the contact members 10 or 11 so as to illuminate either of the lamps 5 or 6.

The design shown by Fig. 1 is well adapted for use as a rear end signal for vehicles for the purpose of indicating that the driver of the vehicle intends to turn either to the right or to the left. The lamp box would be mounted upon the rear end of the vehicle and could be readily controlled by a small electric switch arranged upon the steering wheel or in any other position most convenient to the driver. The design shown by Fig. 2 is well adapted for use as a traffic signal at street intersections since either of the words "Pass" or "Stop" may be displayed to indicate whether the traffic moving along one of the streets is to pass or stop.

Having thus described the invention, what I claim as new and desire to secure by Letters Patent, is:—

1. An illuminated sign including means for producing two forms of light rays of a complemental nature, and an opaque cover plate having transparencies therein forming overlapping designs, those portions of the transparencies common to both of the designs being transparent to both forms of light rays while those portions of the transparencies peculiar to the individual designs are respectively opaque to one form of the light rays and transparent to the other form of the light rays.

2. An illuminated sign including selective means for producing light rays of complemental colors, and an opaque cover plate having overlapping designs formed thereon by transparencies, those portions of the transparencies which are common to both designs being uncolored while those por-

tions of the transparencies which are peculiar to the individual designs have the complementary colors of the light rays so that either one of the designs may be illuminated 5 to the exclusion of the other design by producing light rays of the proper complementary color.

3. An illuminated sign including means for producing light rays of complementary 10 colors, and a cover plate having transparent designs thereon of the same complementary colors of the light rays so that either one of the designs may be illuminated to the exclusion of the other design by producing 15 light rays of the proper complementary color.

4. An illuminated sign including means for producing two forms of light rays of a complementary nature, and a cover plate provided with overlapping designs, those portions of the designs which are common being affected in the same manner by both forms of light rays, while those portions of the designs which are individual are affected in different manners by the two forms of 25 light rays.

5. An illuminated sign including means

for producing two forms of light rays of a complementary nature, and a cover plate provided with overlapping designs, those portions of the designs which are common being transparent to both forms of light rays, while those portions of the designs which are individual are respectively opaque to one form of the light rays and transparent to the other form of the light rays. 30

6. An illuminated sign, including means for producing two forms of light rays of substantially complementary colors, and a transparent design formed in one of the complementary colors of the light rays and 35 mounted to be illuminated by both forms of the light rays, the design being invisible when illuminated by one form of the light rays, and clearly visible when illuminated by the other form of light rays. 40

In testimony whereof I affix my signature in presence of two witnesses.

HARRY F. LÖWENSTEIN.
